AUXILIARY SUN VISOR

Albert A. Seida, P.O. Box 579,
Canby, Oreg. 97013

Filed Mar. 27, 1969, Ser. No. 16,491

Term of patent 14 years

Int. Cl. D12—14

U.S. Cl. D14—6

FIG. 1 is a top view of an auxiliary sun visor showing my new design.

FIG. 2 is an elevational view of FIG. 1.

FIG. 3 is an elevational view taken from the right of FIG. 2 showing the auxiliary sun visor in association with a conventional sun visor, the latter being shown in broken lines for illustrative purposes only.

FIG. 4 is a perspective view of the auxiliary sun visor in an operative position.

I claim:

The ornamental design for an auxiliary sun visor, as shown and described.
